UNITED STATES PATENT OFFICE.

JULIUS J. ACKER, OF CHICAGO, ILLINOIS; IRVIN D. ACKER ADMINISTRATOR OF SAID
JULIUS J. ACKER, DECEASED.

CAR ROOF.

Application filed March 3, 1920. Serial No. 363,073.

To all whom it may concern:

Be it known that I, JULIUS J. ACKER, a citizen of the United States, and a resident of Chicago, county of Cook, and State of Illinois, have invented certain new and useful Improvements in Car Roofs, of which the following is a specification.

The invention relates to weather proof metal covering for car roofs and more particularly to weather proof covering formed of light sheet metal and adapted for use with cars having load-supporting board roofs. The invention seeks to provide an improved structure which is weather and dirt tight and in which the metal roofing sheets are freely movable to a limited extent. The invention consists in the features of improvement hereinafter set forth, illustrated in the preferred form in the accompanying drawings and more particularly pointed out in the appended claims.

In the drawings, Figure 1 is a plan view of a portion of one end of a car roof with the present improved covering applied thereto. Figure 2 is an end elevation of the parts shown in Fig. 1. Figure 3 is a section on the line 3—3 of Fig. 1. Figure 4 is an enlarged detail plan of the portions of the roof sheets and cooperating caps at the center of the roof, the running board saddle being omitted and portions of the caps being broken away. Figure 5 is a perspective view of the parts shown in Fig. 4 and also showing a portion of the running board saddle. Figures 6 and 7 are detail sections on the lines 6—6 and 7—7 respectively of Fig. 4. Figure 8 is a detail section on the line 8—8 of Fig. 1.

The improved weather proof covering is shown applied to a roof structure of ordinary construction comprising side plates 1, a ridge pole 2 and side and roof boards 3 and 4. The roof boards are supported in the usual manner by carlines and also, if desired, by purlines. Fascia boards 5 are secured to the sides of the roof structure by bolts 6 extending through the siding and side plates 1. Preferably, as shown, the fascias are spaced from the siding 3 by spacing blocks 7 arranged at intervals throughout the length of the car and also through which the bolts 6 extend.

The roof sheets or plates 8' and 8'' are formed of sheet metal and preferably extend between the center and sides of the

roof. These sheets have upstanding flanges 9 and 10 at their inner and side edges respectively. The upright flanges 9 at the inner edges of the plates are preferably provided at their upper edges with out-turned, substantially horizontal flanges 11 and the upright side flanges 10 preferably have lips 12 at their upper edges which turn inwardly and downwardly toward the main body portions of the respective sheets. The upright flanges 9 and 10 are preferably connected at their meeting ends by joints, each comprising a lip 13 on one flange that overlaps and is soldered or otherwise suitably secured to the other flange, as shown most clearly in Fig. 4. The outer edges of the sheets extend beyond the side flanges 10 and form downturned eave flanges 14 which are preferably arranged in the spaces between the siding 3 and fascias 5 of the car and between the spacing blocks 7 (see Fig. 8). To stiffen the flange 14, its extreme lower edge is preferably bent upon itself as shown. The outer edges of the roof plates also extend over a flashing 15 of thin sheet metal which overlaps the adjacent edges of the side and roof boards 3 and 4 and is nailed thereto and extends throughout the length of the car.

With the exception of those at the extreme ends of the car, the roof sheets are not nailed or otherwise rigidly secured to the roof structure at any point but are held in position upon the upper surface thereof by longitudinal and transverse caps. The end sheets 8'' are considerably narrower than the intermediate sheets 8' and are provided at their outer side edges with downturned flanges 16 nailed as shown to the adjacent face of the car. (See Fig. 2.)

The transverse caps comprise channel-like portions 17 which extend over the side flanges 10 of the roof sheets and the outer vertical side walls 18 thereof are provided with out-turned foot flanges 19 which engage the upper faces of the roof sheets. The transverse caps are also provided with central U-shaped supporting portions 20 which depend between the side edge flanges 10 and engage the upper face of the board roof 4. The inverted U-shaped channel portions 17 of the transverse caps extend over the side edge flanges 10 of the roof sheets but are spaced therefrom, as most clearly shown in Fig. 6, to permit the limited independent movement of the roof sheets. These channels are

closed at their outer ends by depending portions 21 of the top walls thereof (see Fig. 8) to prevent the entrance of rain, snow, dust and the like. The central portions of the 5 transverse caps extend beyond the ends of the channels 17 and are provided with downturned flanges or extensions 22 which are securely clamped between the fascia boards 5 and the spacing blocks 7 (see Figs. 3 and 10 8), the latter being so arranged that there is one block opposite the outer end of each transverse cap. Preferably, also, the bolts 6 extend through the depending flanges or 15 extensions 22 of the transverse caps.

15 If desired, each transverse cap could extend the entire width of the car roof but preferably, each extends between one side of the car and its center and the inner ends of the caps in alignment are lapped one over the 20 other (see Figs. 3, 4 and 7). It should also be noted that at the inner end portions of the transverse caps, the side walls 18 and foot flanges 19 are omitted.

The central longitudinal caps 23 are of 25 sufficient length to extend between each pair of transverse caps. The upper portions thereof are oppositely inclined in correspondence with the inclination of the portions of the car roof on opposite sides of the 30 ridge pole. The longitudinal caps extend over the inner edge flanges 9 and 11 of the roof sheets and have vertically depending walls 24 at their longitudinal side edges. These walls are provided with inwardly 35 turned foot flanges 25 which engage the upper faces of the roof sheets 8' and 8''. As most clearly shown in Fig. 7, the edges of the flanges 11 and 25 are spaced from the vertical walls 9 and 24 to permit the limited 40 shift of the roof sheets.

As already noted, the side walls 18 and flanges 19 of the transverse caps are omitted or cut away at the inner portions thereof but the side walls 18 are of sufficient length 45 to meet the vertical side walls 24 of the longitudinal caps (see Fig. 4). Beyond this point, the side walls 24 and flanges 25 of the longitudinal caps are cut away or omitted but the upper walls thereof are provided 50 with extensions 26 which project over the raised portions of the transverse caps and have flanges 27 which extend down into the U-shaped portions 20 and fit against the side walls thereof (see Figs. 5 and 6).

55 Running board saddle blocks 28 have horizontal upper faces and lower faces provided with oppositely inclined portions fit within the U-shaped portions 20 of the transverse caps and the lower portions of the saddle 60 blocks are cut away to form shoulders 29 which engage the extensions 26 of the longitudinal caps. Bolts 30 extend centrally through the saddle blocks, through the overlapping ends of the transverse caps and also 65 through the roof boards 4 and ridge pole 2

of the car and are provided with nuts, as shown, on their lower ends. The bolts thus serve to firmly secure the saddle blocks in position, and the latter, by engaging the overlapping ends of the longitudinal and transverse caps, clamp the same to the roof structure. The lower portions of the saddle blocks engage the horizontal portions of the transverse caps which rest directly upon the roof structure so that the clamping pressure of the saddle blocks is not exerted upon the 70 roof sheets. In other words, the U-shaped portions 20 of the transverse caps, and particularly the vertical side walls thereof, form in effect means for supporting the caps directly from the roof structure so that the clamping pressure of the fastening devices by which the parts of the metallic covering are held in place is not exerted on the roof sheets. The latter are, however, held against the upper face of the roof by the foot flanges 19 and 25 which form snug, tight joints therewith but at the same time, the 75 sheets are quite free to move to a limited extent relatively to the caps. Sufficient 80 flexibility is therefore provided to prevent wear and buckling of the roof sheets due to weaving of the car structure.

The heads of the bolts 30 which secure the saddle blocks in place are preferably countersunk in their upper faces and are covered by cap pieces 31 having downturned edge flanges 32 which fit in grooves in the upper face of the saddle blocks, and downturned edge flanges 33 which extend over the side 85 faces of the blocks. One of the latter flanges is preferably of considerable width and is nailed to the saddle block. Also, to avoid leaking of the roof around the bolts, the overlapping portions of the transverse cap 90 pieces are provided with upturned flanges 34 which fit about the bolts, as indicated in Figs. 3, 4 and 7. The usual running boards 35 are mounted on the saddle blocks as 95 shown. In the preferred form set forth, the edge channels 17 of the transverse caps not only support the caps, but strengthen 100 them so that the saddle blocks, fascia boards and the usual clamping bolts therefor are the only securing means required for the 105 weather proof roof covering, except the extreme end sheets and caps, and the covering can be readily applied or sections thereof removed for renewals or repairs. The 110 extreme end sheets 8, as stated, have flanges 115 that are secured to the end faces of the car. Similarly, the end longitudinal caps 23' have downturned flanges 36 that are nailed to the ends of the car (see Fig. 2). Each of the roof sheets can readily shift, as described, to a limited extent and the vertical flanges and walls which limit the movement 120 of the roof sheets are so arranged that when any one sheet is shifted to its extreme limit, its vertical walls or flanges 9, 10 and 14 will 125 130

be brought to bearings at a number of different points so that they cannot be readily bent or distorted. The sheets and caps can be formed of light gauge metal, since they 5 are strengthened by the flanged edge portions thereof. Moreover, the tortuous passages formed by the flanges and the snug joints formed by the resilient pressure of the foot flanges of the caps upon the sheets render the improved roof covering effectively 10 weather and dirt tight.

Obviously, changes may be made in the details set forth without departure from the essentials of the invention as defined in the 15 claims.

I claim as my invention:—

1. In a car roof, the combination with the load-carrying roof structure, of a metal covering therefor comprising a series of sheets 20 extending between the center and sides of the roof and having upstanding flanges at their inner and side edges, longitudinal and transverse caps extending over said flanges and having foot flanges engaging said sheets 25 for holding said sheets in engagement with said roof structure while permitting the independent movement thereof, said caps having supporting portions depending between the flanges of said sheets and provided with 30 flat faces resting on the roof structure, and means for securing said caps to the center and sides of the roof.

2. In a car roof, the combination with the load-carrying roof structure, of a metal covering therefor comprising a series of sheets 35 extending between the center and sides of the roof and having upstanding flanges at their inner and side edges, longitudinal and transverse caps extending over said flanges 40 and having foot flanges engaging said sheets for holding said sheets in engagement with said roof structure while permitting the independent movement thereof, said caps having ends overlapping at the center of the 45 roof, said transverse caps having supporting portions depending between the side edge flanges of said sheets and provided with a flat base resting on the roof structure, and means for clamping the overlapping portions of said caps and the outer end portions 50 of said transverse caps to the roof structure.

3. In a car roof, the combination with the load-carrying roof structure, of a metal covering therefor comprising a series of sheets 55 extending between the center and sides of the roof and having upstanding flanges at their inner and side edges, longitudinal and transverse caps extending over said flanges and having foot flanges engaging said sheets 60 for holding said sheets in engagement with said roof structure while permitting the independent movement thereof, said transverse caps having U-shaped portions depending between the side edge flanges of 65 said sheets into engagement with the roof

structure, and said longitudinal caps having end extensions overlapping the U-shaped portions of said transverse caps, running board saddle blocks fitting within said U-shaped portions, engaging said end extensions and secured to the roof structures, and means for clamping the ends of said transverse caps to the sides of the roof structure. 70

4. In a car roof, the combination with a load-carrying board roof, of a metal covering therefor comprising independently movable sheets extending between the center and sides of the roof and having upstanding flanges at their inner and side edges, longitudinal and transverse caps extending over 75 said flanges and arranged to hold said sheets against said board roof while permitting the independent movement thereof, said caps having overlapping portions at the center of the roof and said transverse caps having 80 U-shaped portions depending between the side edge flanges of the sheets and provided with flat faces resting on the board roof, saddle blocks secured to the roof and clamping the overlapping portions of said caps 85 thereto, and means for clamping the ends of said transverse caps to the sides of the roof. 90

5. In a car roof, the combination with a load-supporting roof structure, of a metal covering therefor comprising a series of sheets 95 extending between the center and sides of the roof, said sheets having upstanding flanges at their inner and side edges and having free outer edges provided with depending eave flanges, and longitudinal and transverse caps extending over 100 and engaging the inner and side edge portions of said sheets to hold the same against the roof structure while permitting the limited independent movement thereof, said transverse caps being secured to the roof structure and having a flat central plate resting on the roof boards between the side 105 edge flanges of said sheets. 110

6. In a car roof, the combination as set forth in claim 5, and fascias spaced from the side edges of the roof structure and extending over the depending eave flanges of said sheets and normally spaced therefrom, the parts being arranged to permit the limited movement of the free outer edge portions 115 of said sheets.

7. In a car roof, the combination with the car siding, a load-carrying board roof and fascias spaced from the side edges of said roof, of a metal covering for the roof comprising a series of roof sheets having upstanding side edge flanges and free outer edges provided with depending flanges arranged in the spaces between said fascias and the side edges of said roof and normally spaced from said fascias, and transverse caps supported by and secured to the roof 120 and extending over and engaging the side 125 130

edge portions of said sheets, the parts being arranged to permit the limited bodily movement of each of said sheets relatively to the car structure.

5 8. In a car roof, the combination as set forth in claim 7, and metal angle strips fixed in position and extending over the meeting edges of the roof and siding and over which the outer edge portions of said 10 sheets extend.

15 9. In a car roof, the combination with a load-supporting board roof, of a light sheet metal covering therefor comprising a series of sheets having upstanding flanges at their side edges, transverse caps having U-shaped 20 central portions resting on the board roof between said edge flanges and said caps having channels extending over and spaced from said edge flanges and provided with 25 foot flanges engaging said sheets, running board saddle blocks resting on the roof-engaging portion of said caps and secured to the roof to clamp said caps to the center of the roof, and means for clamping the outer 30 ends of said caps to the sides of the roof.

35 10. In a car roof, the combination with the side plates, ridge pole, roof boards and saddle blocks and fascias bolted respectively to said ridge pole and said side plates, of a light metal covering for the roof comprising a series of independently movable sheets having edge flanges and transverse caps extending over and engaging the edge portions of said sheets and having supporting portions depending between said side flanges and engaging the substructure of the roof, said caps being clamped to the center and sides of the roof structure by said saddle 40 blocks and fascias respectively.

45 11. In a car roof, the combination with a load-carrying roof structure, of a metal covering therefor comprising a series of independently movable sheets extending between the center and sides of the roof and having upstanding flanges at their inner and side edges and longitudinal and transverse caps secured to the roof structure and ex-

tending over said flanges, said caps having vertical side walls provided with horizontal foot flanges engaging said sheets, the horizontal foot flanges of said longitudinal caps extending toward but spaced from the upstanding inner edge flanges of said sheets, and the latter flanges having horizontal flanges extending outwardly from their upper edges toward but spaced from the vertical side walls of said longitudinal caps.

50 12. In a car roof, the combination with a load-carrying board roof, of a light metal covering therefor comprising a series of independently movable sheets extending between the center and sides of the roof and having upstanding inner and side edge flanges the upper portions of which are provided with flanges extending laterally over the sheets, and longitudinal and transverse caps extending over and spaced from the upstanding and laterally extending flanges of said sheets and having foot flanges engaging said sheets.

55 13. In a car roof, the combination with a load-carrying roof structure, and fascias spaced from the side edges of said roof, of a metal covering therefor comprising a series of independently movable sheets extending between the center and sides of the roof and having depending flanges at their outer edges arranged between said fascias and the side edges of the roof and normally spaced from said fascias, and upstanding flanges at their inner and side edges, and longitudinal and transverse caps secured to the roof and extending over said upstanding flanges, said caps having vertical side walls provided with horizontal foot flanges engaging said sheets, the horizontal foot flanges of said longitudinal caps extending toward but spaced from the upstanding inner edge flanges of said sheets, and the latter flanges having horizontal flanges extending outwardly from their upper edges toward but spaced from the vertical side walls of said longitudinal caps.

60 70 75 80 85 90 95 JULIUS J. ACKER.
